UNITED STATES PATENT OFFICE

HENRY J. LUCKE, OF EAST ORANGE, NEW JERSEY

SAFETY RAZOR

Application filed September 3, 1927. Serial No. 217,416.

My invention relates to improvements in safety razors and especially to means for holding the blade in active or shaving position. In certain aspects the invention is adapted to the use of double-edged blades and to an automatic or self-feeding type of safety razor, but in other aspects the invention is not limited in either of these respects.

10 A principal object is to provide holding means which will more accurately or positively position a blade, and particularly a double-edged blade, on the shaving head, and is at the same time adapted, when incorporated in an automatic-feed type of razor, to permit the movement of the blade to and from working position in the manner normal in that type of instrument.

20 A more particular object in connection with a double-edged blade is to so position and retain the active blade that the idle edge is practically enclosed and protected and is furthermore prevented from coming in contact with any part of the shaving head and thus 25 any dulling or other injury to the inactive edge is prevented; so that when the blade is replaced in the magazine and again fed to active position, the previously unused edge may be presented for shaving in its original 30 sharp and undamaged condition.

35 A further object is to provide for the above objects or results in cooperation with a simple, flat, double-edged blade, free from grooves, slots or other special formations; and to effect the proper positioning and retention of the blade to effect the proper positioning and retention of the blade by so forming and arranging the holding parts that they cooperate 40 with such a simple blade for the purposes and in the manner above and hereafter referred to.

The accompanying drawings show certain representative embodiments of the invention.

45 After considering these examples, skilled persons will understand that many variations may be made without departing from the principles disclosed; and I contemplate the employment of any structures that are properly within the scope of the appended claims.

Fig. 1 is a perspective view of a razor embodying the invention in one form.

Fig. 2 is a section at 2—2, Fig. 1.

Fig. 2a is an enlarged fragmentary section in the same plane.

Fig. 3 is a section at 3—3, Fig. 2.

Fig. 4 is a section similar to Fig. 2, of a modified construction.

Fig. 5 is a section of another modification.

Fig. 1 shows the invention adapted to a known type of automatic-feed or magazine safety razor, and equally well exemplifies one adaptation to an ordinary safety razor, that is, one which has no magazine or automatic feed arrangement. The particular instrument shown includes a hollow handle 1 having at its upper end an angular wall 2 to cooperate with the generally angular or beveled end face 3 of the shaving head 4. This head has a slot 5 and a stem 6 projecting from the end member 2, is pivotally connected to the shaving head by a conventional pivot screw 6' or equivalent, see Figs. 2, 3, 4 and 5, so that when the razor is not in use the latter may be turned into longitudinal alignment with the handle, and when so turned the face 7 of the shaving head is aligned with one side of the slot 8 in the end wall 2, through which a fresh blade is projected from the magazine within the handle 1, by reciprocation of the end knob or cap 9, the blade so positioned sliding under the lip or edge 10 of a curved shield 11 and being retained by frictional pressure of the shield.

As so far described the structure is of a known type, not intended for the use of double-edged blades and in which, if such blades are used, there is no adequate provision for so accurately positioning the blade as to prevent contact of its inner or idle edge with parts of the shaving head such as the wall 12, either in moving to or from active position, and the holding means is moreover not sufficiently positive to accurately position the active or outer edge of the blade in relation to the guard 13 to give the proper spacing for correct shaving action, nor to prevent displacement of the blade by the pressure thereon arising in shaving.

To overcome the above mentioned and

other difficulties or disadvantages of razors of this type I provide improved or additional holding means exemplified in one form in Figs. 1, 2 and 2a, in which a strip of thin sheet spring metal is formed to provide a portion 15 conforming to the inner contour of the shield 11, and secured thereto in any suitable way as by brazing, riveting, etc.

A continuation 16 of the part 15 constitutes 10 in effect a flat or plate spring, terminating in a rounded, downwardly convex or other suitably shaped gripping member 17, which cooperates with a part of the edge formation of the thin wafer blade 18, which preferably 15 has an edge at each of two opposite sides, namely an edge 20 which is in active or outward position, and an edge 20a which is in inward or inactive position. The edge proper is formed by either beveling or hollow-grind- 20 ing the thin steel sheet which constitutes the blade; and my invention is designed to co- operate with either type of edge, that is, straight or hollow-ground, the hollow-grind- 25 ing being represented in Fig. 2 and a straight edge formation in Figs. 4 and 5.

The edge of lip 10 of shield 11 engages the blade as heretofore at a line near the blade center and frictionally clamps to a certain degree the blade upon the head surface 30 11, and at the same time the retainer or bead 17 is yieldingly held by its spring member 16 in engagement with the upper face of the inward blade edge 20a; and this engagement while not absolutely positive, is 35 sufficiently firm and accurate, whether the edge formation is straight or hollow ground, to space i. e., locate and retain definitely said inner edge away from the wall 12 and thus prevent injury to the blade, while the blade 40 is moving endwise to active position and away therefrom, and while it is in active position for shaving. The blade is thus accurately positioned also with respect to its outward edge 20 since the blades are of 45 accurately uniform width and since the inner edge is properly positioned the outer edge is also properly positioned with relation to the guard 13.

The retainer or bead 17 may in some cases 50 be continuous, that is it may extend along the whole length of the spring member 16; otherwise as shown in Fig. 3, the retainer or bead formation may be interrupted, consisting of 55 the short convex or bead formations 17a near the ends of the spring member 16, with an intermediate portion 17b which is free from contact with the blade-edge formation, thus reducing the frictional resistance to the sliding 60 movement of the blade to and from active position, but at the same time positioning and retaining the blade with practically the same security as the long or continuous bead. The ends or corners 17c of the formations 65 17a are slightly beveled or rounded to pre-

vent any retardation of the blade as it is slid endwise to and from position.

Evidently the described holding or retaining device will properly cooperate with a blade of the type described regardless 70 whether the shaving head is incorporated in a magazine (or automatic feed) razor or not, although certain features of the structure are of especial advantage in a device of the type described. 75

Fig. 4 shows a modification in which the retaining bead 17 and its spring member 16 are integral with the shield 11, which is a continuous piece of spring metal and has also formed in it a second bead or lip portion 30 which engages the blade in the same position as the lip 10 of Fig. 2. The function of the bead 17 is here substantially the same as in Fig. 2 and is shown in co-operation with a straight-ground edge, although it would 35 equally well co-operate with a hollow-ground edge.

In the modification of Fig. 5, the retaining members in actual contact with the blade consist of lips or beads 35 and 36, formed 90 on a strip 37 of relatively thick section, this being secured by soldering, riveting or otherwise to the shield 11, the shield in this case furnishing the spring member which holds the bead 35 in engagement with the inner edge formation of the blade and the outer bead 36 in contact with the upper face of the blade. Evidently this device functions substantially as do the others.

My invention is also applicable to the use 420 of single edge blades by providing a locating and retaining means arranged to engage the blunt or unsharpened edge of the blade.

My invention possesses structural advantages in the use of double edge blade razors 430 of the automatic re-fill magazine types, in that the position and path of movement of the blade when shifted from the blade holder is accurately and uniformly determined, thus insuring accuracy in the position of assembling of the blades in the clip or equivalent 440 for storing the once-used blades, preparatory to re-filling.

I claim:

1. A safety razor comprising a shaving head having a surface portion for receiving a blade having parallel surfaces provided with oppositely disposed cutting edges produced by the intersection of two short bevel surfaces, a shield frictionally retaining such a blade upon said surface with the outward sharpened edge exposed for shaving, and means yieldably engaging the taper of the inward sharpened edge portion of the blade whereby to position the outward edge.

2. A safety razor comprising a shaving head having a surface portion for receiving a thin wafer blade having its opposite edges sharpened, a shield frictionally retaining such a thin wafer blade upon said surface

with the outward sharpened edge exposed for shaving, and means yieldably engaging the taper of the inward sharpened edge portion of the blade whereby to resist lateral displacement thereof and also to position the outward edge.

3. A safety razor comprising a shaving head having a surface portion for receiving a thin wafer blade having its opposite edges sharpened, a shield frictionally retaining such a blade upon said surface with the outward sharpened edge exposed for shaving, said shield also having yieldable means engaging the taper of the inward sharpened edge portion of the blade adjacent the cutting edge thereof and resisting lateral displacement thereof.

4. A safety razor comprising a shaving head having a surface portion for receiving a blade having parallel surfaces provided with oppositely disposed cutting edges produced by the intersection of two short bevel surfaces, a shield frictionally retaining such a blade upon said surface with the outward sharpened edge exposed for shaving, and means yieldably engaging the taper of the inward sharpened edge portion of the blade whereby to position the outward edge, said shield and yieldable means being adapted to permit longitudinal sliding of the blade to and from active position.

5. A safety razor comprising a shaving head having a surface portion for receiving a flat thin wafer blade having its opposite edges sharpened and a wall extending at an angle therefrom, a shield adapted to engage such a flat, thin wafer blade and frictionally retain it upon said surface portion, and a bead member yieldably supported and adapted to engage the taper of the inward sharpened edge formation of the thin wafer blade, keep it from contact with said wall, and accurately position the outward edge thereof for shaving.

45 6. A safety razor comprising a shaving head having a surface portion for receiving a flat thin wafer blade having its opposite edges sharpened and a wall extending at an angle therefrom, a shield adapted to engage such a flat, thin wafer blade and frictionally retain it upon said surface, and a bead member yieldably supported and adapted to engage an inward edge formation of the blade, keep it from contact with said wall, and accurately position the outward edge for shaving, said bead member being adapted to permit longitudinal sliding of the blade to and from active position.

7. A safety razor comprising a shaving head having a surface portion for receiving a flat thin wafer blade having its opposite edges sharpened and a guard space from the outward edge of said surface, a shield having means for frictionally retaining such a thin, flat, double-edged blade upon said

surface, and means in cooperation with said shield for yieldingly engaging the taper of the inward sharpened edge formation of the blade and thereby locating the outward sharpened edge with relation to the guard and preventing contact of the inner edge with said wall.

8. A safety razor of the class described, comprising a head having a surface portion for receiving a blade having its opposite edges sharpened and an upward projection at the rear thereof, a shield, and means cooperating with the shield and the taper of the inward sharpened edge formation of such a blade to definitely locate the latter in active position, said means constructed and arranged to permit longitudinal sliding of the blade to and from active position.

9. A safety razor comprising a shaving head having a blade-engaging surface portion, a shield frictionally retaining a double edged blade upon said surface with outward sharpened edge exposed for shaving, and means engaging the taper of the inward sharpened edge portion of the blade adjacent the cutting edge thereof whereby to retain the outer edge in operable position.

10. A safety razor comprising a shaving head having a blade-engaging surface portion, a shield adapted to engage and retain a blade having parallel surfaces provided with oppositely disposed cutting edges produced by the intersection of two short bevel surfaces upon said blade-engaging surface, with the outward sharpened edge exposed for shaving, and means for engaging the taper of the inward sharpened edge adjacent thereto whereby to retain the blade in operable position.

In testimony whereof I have signed this specification this 2nd day of September, 1927.
